DESIGN FOR A COMBINATION CABINET AND TABLE

Herbert H. Twente, Independence, Mo.

Application January 4, 1945, Serial No. 117,249

Term of patent 7 years

(Cl. D33—13)

To all whom it may concern:

Be it known that I, Herbert H. Twente, a citizen of the United States, residing at Independence, in the county of Jackson and State of Missouri, have invented a new, original, and ornamental Design for a Combination Cabinet and Table, of which the following is a specification, reference being had to the accompanying drawings, forming a part thereof.

Fig. 1 is a perspective view of the combination cabinet and table, in closed condition, showing my new design.

Fig. 2 is a side elevational view thereof.

Fig. 3 is a plan view of the combination cabinet and table; and

Fig. 4 is a perspective view of the combination cabinet and table in opened condition.

I claim:

The ornamental design for a combination cabinet and table, as shown.

HERBERT H. TWENTE.
